UNITED STATES PATENT OFFICE.

WALTER A. CROWDUS, OF CHICAGO, ILLINOIS.

DESIGN FOR A VEHICLE-FRAME.

SPECIFICATION forming part of Design No. 34,827, dated July 23, 1901.

Application filed June 25, 1901. Serial No. 66,015. Term of patent 14 years.

To all whom it may concern:

Be it known that I, WALTER A. CROWDUS, a citizen of the United States, and a resident of Chicago, in the county of Cook and State of Illinois, have invented and produced a new and original Design for a Vehicle-Frame, of which the following is a specification.

In the accompanying drawings, Figures 1, 2, 3, and 4 are respectively top plan, side, front, and rear views of a vehicle-frame of my design.

A vehicle-frame of my design comprises front and rear axle-supports A A', side-bars A², and struts or braces A³.

In general design the front and rear axle-supports A A' are upwardly bowed or arched between their ends and comprise upward extensions or arms a a', respectively.

The rear axle-support A' of a vehicle-frame

of my design also comprises arms a², which depend therefrom and are located adjacent to the middle thereof.

The side-bars A² connect the upward extensions a a' of the front and rear axle-supports, and the struts or braces A³ extend from points adjacent to the ends of the front and rear axle-supports to said side-bars.

I claim—

The design for a vehicle-frame, substantially as herein shown and described.

In testimony that I claim the foregoing as my invention I affix my signature, in presence of two subscribing witnesses, this 25th day of May, A. D. 1901.

WALTER A. CROWDUS.
